UNITED STATES PATENT OFFICE.

CLINTON B. REPP, OF NEW YORK, N. Y., ASSIGNOR, BY MESNE ASSIGNMENTS, TO
GUILLERMO H. ALONSO, OF NEW YORK, N. Y.

PHONOGRAPH.

1,302,433.

Specification of Letters Patent. Patented Apr. 29, 1919.

Application filed June 2, 1911. Serial No. 630,882.

To all whom it may concern:

Be it known that I, CLINTON B. REPP, a citizen of the United States, residing at the borough of Manhattan, in the city, county, and State of New York, have invented certain new and useful Improvements in Phonographs, of which the following is a specification, reference being had therein to the accompanying drawings, which form a part thereof.

My invention relates to phonographs, and more particularly to a convertible instrument adapted to be used either as a graphophone or as a gramophone.

The main object of this invention is to provide a phonograph wherein the indicated sound waves are transmitted through a vibrator member to a diaphragm placed under tension through said vibratory member, wherein the direction of the application of stress or pressure upon the diaphragm may be varied to adapt the machine to use with records wherein the indicated sound waves have a vertical undulation, or records wherein such indicated sound waves have a lateral undulation. A further object is to provide in a machine of this character means applying pressure upon the stylus point through an auxiliary supporting or controlling arm, the connecting means between this arm and the vibratory member being so constructed as to permit that change in the position of the vibrator member incidental to the change in the direction of the application of pressure therethrough to the diaphragm. A still further object is to provide a machine of this character wherein any variance in the arcs described by the vibrator member and by the auxiliary supporting or controlling arm will be automatically compensated for in a manner to avoid any false tone in the reproduced sounds. A still further object is to provide a machine of this character wherein the pressure will be placed upon the diaphragm by means of a spring and a loop member capable of movement relative to the diaphragm, the means tensioning the said spring being capable of such adjustment as to vary the direction of the application of pressure without materially varying the degree of such pressure. A still further object is to provide a machine of this character wherein the auxiliary controlling

or supporting arm will be so supported and will have the requisite pressure so applied thereto, through the spring, as to avoid the development of independent vibrations in said spring or any retardation of said arm in following the indicated sound waves upon a record under the control of the vibrator member. A still further object is to provide in a machine of this character a concealed horn so constructed and arranged relative to the sound box as to permit said horn to have vertical movement relative to the sound box without disconnecting the horn from the sound outlet of said box. A still further object is to provide in a machine of this character a concealed horn so related to the outlet of the sound box as to permit the concealed horn to be disconnected from said outlet and the substitution of an ordinary horn therefor. And a still further object is to provide a machine of this character, the various parts of which will be so constructed and arranged as to minimize likelihood of the development of such vibrations as would interfere with or impair the sound vibrations indicated upon the record passing to the diaphragm while permitting the machine to be economically produced.

The invention consists primarily in the combination in a phonograph, of an amplifier, a vibrator member, means capable of movement relative to said amplifier, connecting said vibrator member with said amplifier, means applying pressure to said amplifier in a direction opposite to the direction of the vibrations passing thereto, and means varying the direction of the application of pressure by said last named means whereby both vertical and lateral vibrations may be transmitted through said vibrator member to said amplifier; and in such other novel features of construction and combination of parts as are hereinafter set forth and described and more particularly pointed out in the claims hereto appended.

Referring to the drawings:

Figure 1 is a front view in perspective, of the sound reproducing means of my improved phonograph;

Fig. 2 is a rear elevation thereof;

Fig. 3 is a detail view of the mount of the vibrator member;

cabinet; showing the sound reproducing means in elevation;

Fig. 5 is a horizontal section on the line 5—5 of Fig. 4, showing the horn in elevation, 5 and

Fig. 6 is a rear view of the upper part of the cabinet.

Like letters refer to like parts throughout the several views.

- 10 In the embodiment of my invention shown in the accompanying drawings, I have shown at *a* a cabinet carrying a rotatable platform *b*. The means actuating said platform are not shown, as such are well known in the art and immaterial to the invention. Spaced away from and at one side of the platform *b* is a sound box *c* of the ordinary, or any desired or approved type, having a sound outlet *c'* and carrying a diaphragm *c*²
- 15 20 indicated in dotted lines Fig. 1. Said sound box is raised above the plane of the platform *b* by a plurality of standards *d*.

Extending from the diaphragm *c*² toward the platform *b* is a vibrator member *e*, of material adapted to transmit sound vibrations to said diaphragm, as indicated by a record, such material preferably being wood.

One end of the vibrator member *e* carries a mount *f* for the stylus or reproducer point 30 *f*², and the other end thereof carries an open loop *e'* passing through and engaging a loop *g* carried by the stud *c*³ which extends through and is attached to, the diaphragm *c*². The loop *g* while preferably consisting 35 of a strand of silk or cat gut, may be made of any desired material, so long as it possesses sufficient flexibility of movement to be capable of movement relative to the diaphragm and of placing the diaphragm under 40 pressure acting in a direction toward the vibrator member *e*.

Acting upon the vibrator member *e*, and through said member and the loop *g* upon the diaphragm, is a spring or other tensioning means *h*, the free end of which is attached to tensioning means mounted upon 45 one of the standards *d*.

In machines of this character, it has been demonstrated that to effectively transmit 50 sound vibrations indicated upon a record through the vibrator member to the diaphragm, it is essential that the entire transmission mechanism should be in tension and that the means applying the tension to the 55 connecting means between the vibrator arm and the diaphragm must be applied in a direction opposite to the movement of the vibrations in passing to the diaphragm, with a resultant tensioning of the diaphragm.

60 Machines heretofore designed by me embodying this principle, have been adapted for use only in connection with records having vertical undulatory lines thereon, or gramophone records, and were not capable 65 of use with records having lateral undula-

tions, or gramophone records. In the machine shown in the accompanying drawings, however, I apply the pressure of the spring *h* at an angle to the axis of the diaphragm *c*² so as to adapt the machine for use in 70 connection with gramophone records, thus bringing the line of the force exerted into consonance with the lateral vibrations passing through the member *e*.

In order that the machine adapted for reproducing sounds from gramophone records, the tensioning means for the spring *h* consists of a pivoted lever *i*, the arm of said lever to which the spring is connected, being of a length sufficient to bring 80 the end of the spring below the point of connection between the loop *g* and the diaphragm, or in alinement with the axis of said diaphragm.

To secure the proper adjustment of the 85 lever *i*, I provide said lever with a guide slot *i'* having enlargements *i*² at the opposite ends thereof, a set screw *j* connected to the standard *d* supporting said lever, passing through said slot and having an enlarged 90 head adapted to enter said enlargements and prevent the accidental displacement of said lever through the tension of said spring and the loosening of said set screw. It will be readily observed that by this construction, 95 the raising or lowering of the arm of the lever *i* to which the spring *h* is attached, will vary the direction of the pressure applied to the loop *g* and through it to the diaphragm *c*², the pressure so applied being 100 either axially of said diaphragm or at an angle to, and laterally of said axis.

Axially below the diaphragm *c*² is a post *k* having a horizontal slot *k'* therein, said post having revolvably mounted therein a 105 fork *l* having a screw threaded stem *l'* co-operating with screw threads in said post and of a length sufficient to extend across said slot *k'*.

Mounted in the fork *l* by means of horizontal 110 pivots *l*² is a forwardly projected supporting or controlling arm *m* through which the requisite pressure of the stylus upon the record is developed. The forward end of the arm *m* is connected to the vibrator member *e* adjacent the mount *f*, insulation being used between the member *e* and the connecting means to prevent the development of vibrations in the arm *m*. The revolvable stem *l'* and the pivots *l*² having axes perpendicular to each other, the arm *m* is free to rock vertically or swing laterally with the movement of the vibrator member *e* in following the record, said arm *m* at all times determining and maintaining the proper position 115 of said vibrator member relative to the record.

Pendant from the arm *m* is a post *n* having a series of recesses along the length thereof adjacent said arm, the lower portion 120

125 130 of said arm being adjacent said post *n*.

of said arm extending at an angle toward the post *k* terminating adjacent to said post in a manner to support the arm *m* and the vibrator member *e* when the stylus point is disengaged from the record. Connected with the post *n* at one end with the stem *l'* at the other end, is a spring *o* which by reason of its acting upon the post below the arm *m* exerts sufficient downward pressure upon 5 said arm to secure the desired pressure of the stylus upon the record. By shifting the connecting point between said spring and said post *n* upwardly or downwardly, this pressure may be lessened or increased as desired, 10 the notches along said post holding the spring in any adjusted position.

Owing to that shifting of the member *e* incidental to converting the instrument from a gramophone to a graphophone, or vice 20 versa, I incorporate in the connecting means between the vibrator member *e* and its supporting and controlling arm *m* a universal joint so as to permit the requisite shifting of the vibrator member *e* relative to the supporting and controlling arm *m* without subjecting said member *e* to such stresses as would vary the normal molecular condition thereof. The universal joint above referred to is formed by spreading the outer end of 25 the arm *m* and forming a loop *p* thereon which is turned upwardly. Mounted in this loop by means of horizontal pivots is a ring *p'* having pivotally supported therein by means of vertical pivots, the oppositely disposed shoes *p''* conforming to and bearing upon the member *e*, vibration absorbent material being disposed between said shoes and the member *e* to prevent the escape of vibrations to said arm *m*. This form of joint 30 permits the member *e* to be shifted to vary the direction of the pressure applied to the diaphragm, the universal pivotal support for the arm *m* permitting said member *e* to move freely in any direction without pivotal movement upon the universal joint. By connecting the spring *o* to the stem *l'* of the fork *l*, 35 no friction between the spring and said stem is developed with the lateral movement of the arm *m* thus not only avoiding slight retardation of said arm, but at the same time avoiding the development of vibration in said spring which might tend to impair the efficiency of the machine.

The absence of cross vibrations throughout the apparatus being a desideratum, I provide a special form of mount and secure it to the vibrator member *e* in a special manner to avoid any possible looseness of said mount with resultant slight rattling which 40 would develop serious blasts from the instrument when in operation. This mount consists of an orificed head carrying a set screw *f'* for securing the point *f''* firmly in position, said head being provided with a 45 screw threaded stem *f''* which is driven into

and firmly embedded in the material of which said arm is made. This manner of attaching the mount so compresses the material of the arm about the screw as to prevent it from shrinking away from the 70 mount, and thus secures it firmly in place. The screw extends at an angle through the member *e*, and the exposed top thereof is finished to conform with the surface of the arm.

The entire mechanism heretofore described rests upon a base adapted to contain the driving mechanism for the platform *b*, which base forms a part of the cabinet *a*. This mechanism is inclosed by a cover *q* 80 mounted within which is a horn *r* projecting over the platform *b*. The front of this cover is close by means of the hinged doors *q'* having sound outlet openings *q''* at the top and bottom thereof, the horn being supported by the door frame in a fixed position relative to said cover and including said openings. The back of the cover has an opening *q'''* therein adapted to provide clearance for the conduit system between 90 said horn and the sound outlet opening of the sound box.

The cover *q* is hinged at *q''* adjacent to said opening, and as it is turned upwardly carries with it the entire horn, exposing the 95 works of the machine so as to permit the placing or removal of records upon or from the platform *b*. To permit this opening of the cover, it is necessary to provide a special joint in the conduit system connecting 100 the horn with the sound box and a specially constructed system of sound conduits, which will now be described.

Extending longitudinally of the machine is a tube *s* having a coupling sleeve *s'* at 105 the forward end thereof adapted to slip over and engage the sound outlet nozzle *c'* of the sound box *c*. The rear end of this tube is provided with an elbow *s''* which is connected with a corresponding elbow *s'''* carried by the horn *r*, by means of a coupling member *t* consisting of two members united by means of a screw thread. The adjacent arms of the elbows *s''* and *s'''* are alined with each other and their axes are in exact alinement with the axes of the hinges for the cover so that as the cover is raised, or lowered, the elbow *s'''* may turn freely with relation to the elbow *s''* and thus prevent the 115 movement of the cover from interfering in any way with the said conduit system.

The coupling *s'* has a tight sliding fit with the nipple of the sound outlet so that it may be readily disengaged, if desired, and an ordinary outside horn applied to the instrument in lieu of the concealed horn.

The operation of the herein described phonograph is substantially as follows:—

The point *f''* is inserted in the mount and secured in place by the set screw *f*, 120

and is then placed upon the record in engagement with the spirally indicated sound waves in the usual manner. As the platform *b* rotates, the record sets up vibrations in the vibrator member *e* which pass along said member to the loop *g* and through said loop to the diaphragm *c*², the member *e* having no movement in its entirety except about a pivotal point where the loop *e* engages the loop *g*. The diaphragm being under tension through the stress or pressure thereon from the spring *h*, is very sensitive to the vibrations passing thereto, and quickly returns to normal owing to the fact that the action of the spring *h* is constant and acts directly upon said diaphragm through the loop *g*. Said spring *h* also applies such pressure in a line or direction opposite to the direction of line of movement of the sound vibrations passing into the diaphragm.

The point *f*³ is held, with the requisite pressure, upon the record by the spring *o* through the controlling or supporting arm *m*, which is capable of oscillatory movement about a compound axis directly below the axis of the diaphragm. The said arm is permitted to follow the arm *e* whether it moves vertically or laterally under the control of the record, and any irregularities in the record, or in the platform *b*, are compensated for. The arm *m* nevertheless, always defines the arc through which the point *f*³ must travel, the vibrator member *e* at all times being under the control of said arm *m*.

When it is desired to use the machine with a gramophone record, the spring *h* is caused to exert a pressure upon the diaphragm laterally of the machine, thus causing the direction of the pressure tensioning the diaphragm and the loop *g* to be in a line opposite to the direction of movement of the sound vibrations in passing through the vibrator member *e* and the said loop, which with a gramophone record would be laterally of said member *e*. If, however, it be desired to use the machine with a graphophone record, the set screw *j* is released and the lever *i* swung so as to cause the spring *h* to extend substantially axially of the diaphragm *c*², as shown in dotted lines in Fig. 2, thus varying the direction of the pressure applied to the diaphragm through the loop *g* so as to bring said pressure in a direction opposite to the movement of the vertical vibrations passing through said member *e* and loop *g* to said diaphragm.

As the inner end of the vibrator member *e* is thus shifted relative to the diaphragm, the universal joint through which the outer end of said member is supported and controlled by the arm *m*, permits the member *e* to shift relative to the arm *m* while at the same time avoiding any looseness in the con-

nection between said member and said arm. This conversion of the machine from a gramophone to a graphophone or vice versa, is accomplished by the variance in the direction of the pressure applied through the loop *g* to the diaphragm, no other adjustment being required, or if required, being automatic. Owing to the fact that the pressure exerted through the spring *h* will amount to several ounces, it is desirable to provide positive means locking the lever *i* in either adjusted position, which I accomplish by the construction above referred to.

The flexibility of the loop *g* will not only permit the adjustment above referred to, but will, by a slight oscillatory movement longitudinally of the machine, compensate for the arc described by the inner end of said member when shifted to accomplish such adjustment, and also compensate for that slight eccentricity of centers about which the arm *m* and member *e* pivot in following the record when the machine is used as a gramophone.

The operation of the horn located in the cover of the machine is apparent from the description of the construction thereof, it being evident that the cover *q* and the loop *s*³ carrying the horn turn about the same axis with the raising of the cover.

The reach of the tubular conduit extending from the sound box elongates the passage through which the sound waves pass before being delivered, thus increasing the efficiency of the amplifying mechanism with a compact structure. Furthermore the detachability of the coupling member *s*⁴ from the nipple forming the sound outlet, permits the cover *q* to be raised and the concealed horn *r* to be disconnected from the sound box and an ordinary horn to be applied thereto.

It is not my intention to limit the invention to the precise details of construction shown in the accompanying drawings, it being apparent that such may be varied without departing from the spirit or scope of the invention.

I believe it to be broadly new to provide an instrument wherein the sound vibrations are transmitted through a vibrator member to a diaphragm subjected to pressure, embodying therein means for varying the direction of this pressure applied to the diaphragm to convert the instrument into either a gramophone or graphophone as desired.

I also believe it to be broadly new to provide a machine wherein sound vibrations are transmitted through a vibrator member to the diaphragm, embodying therein tensioning means acting laterally of and at an angle to the diaphragm, to permit the transmission of lateral sound vibrations along said vibrator member to the diaphragm.

Having described my invention, what I

claim as new and desire to have protected by Letters Patent, is:

1. In a phonograph, an amplifier, a vibrator member adapted to receive vibrations from a record and transmit them to said amplifier, means capable of movement relatively to said amplifier connecting said vibrator member with said amplifier, means tensioning said amplifier through said means in a direction opposite to the direction of the vibrations passing thereto, and means varying the direction of the application of the tension by said last named means whereby both vertical and lateral vibrations may be transmitted through said vibrator member to said amplifier.

2: In a phonograph, an amplifier, a vibrator member adapted to receive vibrations from a record and transmit them to said amplifier, means capable of movement relatively to said amplifier, connecting said vibrator member with said amplifier, a spring tensioning said amplifier through said means in a direction opposite to the direction of the vibrations passing thereto, and a movable tensioning member acting on said spring whereby the position of said spring may be changed to vary the direction of the application of the tension by said spring to permit either lateral or vertical vibrations to be transmitted through said vibrator member to said amplifier.

3. In a phonograph, an amplifier, a vibrator member adapted to receive vibrations from a record and transmit them to said amplifier, means capable of movement relatively to said amplifier, connecting said vibrator member with said amplifier, a spring tensioning said amplifier through said means in a direction opposite to the direction of the vibrations passing thereto, an oscillatory lever acting on said spring whereby the position of said spring may be changed to vary the direction of the application of the tension by said spring to permit either lateral or vertical vibrations to be transmitted through said vibrator member to said amplifier, and means locking said lever in position.

4. In a phonograph, an amplifier, a vibrator member, a supporting and controlling arm for said vibrator member movable at one end about a compound axis and connected at the other end with said vibrator member by a universal joint, means exerting downward pressure upon said arm, means capable of movement relatively to said amplifier connecting said vibrator member with said amplifier, means tensioning said amplifier through said means in a direction opposite to the direction of the vibrations passing thereto, and means varying the direction of the application of the tension by said last named means whereby both vertical and lateral vibrations may be

transmitted through said vibrator member to said amplifier.

5. In a phonograph, an amplifier, a vibrator member, a supporting and controlling arm for said vibrator member movable at one end about a compound axis and connected at the other end with said vibrator member by a universal joint, means exerting downward pressure upon said arm, means whereby such downward pressure may be varied, means capable of movement relatively to said amplifier connecting said vibrator member with said amplifier, means tensioning said amplifier through said means in a direction opposite to the direction of the vibrations passing thereto, and means varying the direction of the application of the tension by said last named means whereby both vertical and lateral vibrations may be transmitted through said vibrator member to said amplifier.

6. In a phonograph, an amplifier, a post axially below said amplifier, a yoke movable about a vertical axis mounted in said post, a supporting or controlling arm, one end of which is mounted on horizontal pivots in said yoke, a vibrator member, a universal joint connecting the other end of said arm with said vibrator member, means exerting a downward pressure upon said arm, means capable of movement relatively to said amplifier connecting said vibrator member with said amplifier, means tensioning said amplifier through said means in a direction opposite to the direction of the vibrations passing thereto, and means varying the direction of the application of the tension by said last named means whereby both vertical and lateral vibrations may be transmitted through said vibrator member to said amplifier.

7. In a phonograph, an amplifier, a vibrator member, a supporting or controlling arm for said vibrator member, a universal pivotal support for the end of said arm adjacent said amplifier, shoes engaging said vibrator member, a ring pivotal connections between said ring and said shoes, means pivotally supporting said ring from said arm by pivots extending at right angles to the pivots between said shoes and said ring, means exerting a downward pressure upon said arm, means capable of movement relatively to said amplifier connecting said vibrator member with said amplifier, means tensioning said amplifier through said means in a direction opposite to the direction of the vibrations passing thereto, and means varying the direction of the application of the tension by said last named means whereby both vertical and lateral vibrations may be transmitted through said vibrator member to said amplifier.

8. In a phonograph, a diaphragm, a vibrator member, a flexible loop connecting

said vibrator member and said diaphragm, means tensioning said diaphragm through said loop and said vibrator member in a direction opposite to the direction of the 5 vibrations passing thereto, and means varying the direction of the application of the tension by said last named means whereby both vertical and lateral vibrations may be transmitted through said vibrator member

10 to said diaphragm.

9. In a phonograph, an amplifier, a post axially below said amplifier, a yoke movable about a vertical axis mounted in said post, a supporting or controlling arm, one end of which is mounted on horizontal pivots in said yoke, a vibrator member, a universal joint-connecting the other end of said arm with said vibrator member, means exerting a downward pressure upon said arm, means 15 projecting from said supporting or controlling arm and extending into close juxtaposition to said post whereby said arm may be held against excessive downward movement, means capable of movement relatively 20 to said amplifier connecting said vibrator member with said amplifier, means tensioning said amplifier through said means in a direction opposite to the direction of the vibrations passing thereto, and means varying 25 the direction of the application of the tension by said last named means whereby both vertical and lateral vibrations may be transmitted through said vibrator member to said amplifier.

30 10. A phonograph embodying therein a flexible diaphragm, a wooden transmitter arm, a connection between one end of said arm and said diaphragm, and a metallic mount carried by the other end of said arm 35 comprising a head having a socket adapted to receive a stylus, a screw threaded stem of smaller dimensions than said head whereby a shoulder is formed thereabout, said stem being adapted to draw said shoulder 40 tightly against the end of said arm, and to be firmly embedded in the fiber thereof, and means carried by said head whereby a stylus 45 may be secured in said socket.

11. In a phonograph, an amplifier, a 50 vibrator member, means connecting said vibrator member with said amplifier, means tensioning said amplifier laterally of said vibrator member and at an angle to the axis of said amplifier, whereby lateral vibrations passing through said vibrator will be 55 transmitted to said amplifier, and means forcing said vibrator member toward the record.

12. In a phonograph or talking machine, 60 the combination of a record support, a reproducer in operative relation thereto, a cover for said record support and reproducer pivoted for movement about a horizontal axis, and a continuous sound conveyer connected with said reproducer and having a 65

plurality of communicating sections, one of which is mounted for pivotal movement relatively to the other about the pivotal axis of the cover, said axis being so arranged that the length of the conveyer remains unchanged and the conveyer sections remain in complete register with each other during the relative movement of said sections about said axis, substantially as described. 70

13. In a phonograph or talking machine, 75 the combination of a record support, a reproducer in operative relation thereto, a cover for said record support and reproducer pivoted for movement about a horizontal axis, and a continuous sound conveyer connected with said reproducer and having a plurality of communicating sections, one of which is pivoted for movement relatively to the other about the pivotal axis of the cover, said axis passing through the central 80 axis of said sound conveyer and being so arranged that the conveyer sections remain in complete register with each other during their relative movement about said axis, substantially as described. 90

14. In a phonograph or talking machine, the combination of a record support, a reproducer in operative relation thereto, a cover for said record support and reproducer pivoted for movement about a horizontal 95 axis, and a continuous sound conveyer with said reproducer and having a plurality of communicating sections, one of which is movable with said cover, the communicating ends of said conveyer sections being relatively 100 movable about said axis but immovable toward and away from each other or out of register with each other upon the opening or closing of the cover, substantially as described. 105

15. In a phonograph or talking machine, the combination of a record support, a reproducer in operative relation thereto, a cover for said record support and reproducer pivoted for movement about a horizontal axis, 110 and a continuous sound conveyer connected with said reproducer and having a plurality of communicating sections, one of which is movable with said cover, the communicating portions of said conveyer sections being relatively 115 movable about said axis but immovable relatively to each other in the directions of their axes or out of register with each other upon the opening or closing of the cover, substantially as described. 120

16. In a phonograph or talking machine, the combination of a record support, a reproducer in operative relation thereto, a cover for said record support and reproducer pivoted for movement about a horizontal 125 axis, and a continuous sound conveyer connected with said reproducer and having a plurality of communicating sections, one of which is movable with said cover, the communicating portions of said conveyer sec- 130

tions having their axes coincident with the pivotal axis of said cover and being relatively movable about said axis, substantially as described.

17. In a phonograph or talking machine, the combination of sound reproducing apparatus, a pivoted cover therefor, having movement about a horizontal axis and a sound amplifier movable with said cover and having a substantially horizontally projecting portion pivotally connected to said sound reproducing apparatus on a horizontal axis, the pivotal axes of said cover and amplifier being coincident substantially as described.

18. In a phonograph, a cabinet having a base, a rotatable table supported thereby, means whereby said table may be rotated, a reproducing mechanism including an immovable sound box, a cover hinged adjacent said base, a horn carried by and movable with said cover, and a conduit system embodying therein two angular sections, one end of said sections respectively being connected with said sound box and said horn, and the other ends of said sections being in communication with each other and a swivel connection between said ends, the axis of said connection being in substantial alinement with the axis of said hinges.

19. In a phonograph, a cabinet having a base, a rotatable table supported thereby, means whereby said table may be rotated, a reproducing mechanism including an immovable sound box, a cover hinged adjacent said base, a horn carried by and movable with said cover, a conduit system embodying therein two angular sections, one end of said sections respectively being connected with said sound box and said horn, and the other

ends of said sections being in communication with each other, and a swivel connection between said ends, the axis of said connection being in substantial alinement with the axis of said hinges, and doors carried by said cover extending across the mouth of said horn, said doors having openings therein communicating with said horn.

20. In a phonograph, a reproducing mechanism embodying therein a stationary sound box having a nipple surrounding the outlet opening thereof, a concealed horn, a conduit system, one end of which is adapted to be connected with said horn and the other end of which is adapted to be connected with the nipple of said sound box, one end of said system having a pivotal relation to the other, whereby the end connected to the sound box may be disconnected therefrom to permit the instrument to be used with either said concealed horn or with an exposed horn.

21. In a phonograph, a reproducing mechanism embodying therein a stationary sound box having an upwardly directed sound outlet opening, a projecting nipple surrounding said opening, a concealed horn having an inlet adjacent to said sound box, and a conduit adapted to detachably engage said nipple and to communicate with the inlet of said concealed horn, whereby said concealed horn may be connected with said sound box or disconnected therefrom to permit the use of an exposed horn.

In witness whereof, I have hereunto affixed my signature in the presence of two witnesses, this 31st day of May, 1911.

CLINTON B. REPP.
